[57] CLAIM

The ornamental design for a dual-level ceiling for a
store interior, as shown.

DESCRIPTION

FIG. 1 is a perspective view of a dual-level ceiling for a
store interior showing our new design;

FIG. 2 is another perspective view thereof taken at a
slightly different angle; and

FIG. 3 is an enlarged detail perspective view of a portion
of the ceiling thereof.

FIG. 1

FIG. 2

FIG. 3
